DESCRIPTION

FIG. 1 shows a perspective view of a first embodiment of a design for an integrated tabbed note and clip kit.

FIG. 2 shows a top view of the first embodiment.

FIG. 3 shows a front view of the first embodiment.

FIG. 4 shows a right-side view of the first embodiment. A left-side view of this embodiment is a mirror image of this figure.

FIG. 5 shows a back view of the first embodiment.

FIG. 6 shows a bottom view of the first embodiment.

FIG. 7 shows a perspective view of a second embodiment of a design for an integrated tabbed note and clip kit.

FIG. 8 shows a top view of the second embodiment.

FIG. 9 shows a front view of the second embodiment.

FIG. 10 shows a right-side view of the second embodiment. A left-side view of this embodiment is a mirror image of this figure.

FIG. 11 shows a back view of the second embodiment.

FIG. 12 shows a bottom view of the second embodiment.

FIG. 13 shows a perspective view of a third embodiment of a design for an integrated tabbed note and clip kit.

FIG. 14 shows a top view of the third embodiment.

FIG. 15 shows a front view of the third embodiment.

FIG. 16 shows a right-side view of the third embodiment. A left-side view of this embodiment is a mirror image of this figure.

FIG. 17 shows a back view of the third embodiment.

FIG. 18 shows a bottom view of the third embodiment.

FIG. 19 shows a perspective view of a fourth embodiment of a design for an integrated tabbed note and clip kit.

FIG. 20 shows a top view of the fourth embodiment.

FIG. 21 shows a front view of the fourth embodiment.

FIG. 22 shows a right-side view of the fourth embodiment. A left-side view of this embodiment is a mirror image of this figure.

FIG. 23 shows a back view of the fourth embodiment.

FIG. 24 shows a bottom view of the fourth embodiment.

FIG. 25 shows a perspective view of a fifth embodiment of a design for an integrated tabbed note and clip kit.

FIG. 26 shows a top view of the fifth embodiment.

FIG. 27 shows a front view of the fifth embodiment.

FIG. 28 shows a right-side view of the fifth embodiment. A left-side view of this embodiment is a mirror image of this figure.

FIG. 29 shows a back view of the fifth embodiment.

FIG. 30 shows a bottom view of the fifth embodiment.

FIG. 31 shows a perspective view of a sixth embodiment of a design for an integrated tabbed note and clip kit.

FIG. 32 shows a top view of the sixth embodiment.

FIG. 33 shows a front view of the sixth embodiment.

FIG. 34 shows a right-side view of the sixth embodiment. A left-side view of this embodiment is a mirror image of this figure.

FIG. 35 shows a back view of the sixth embodiment.

FIG. 36 shows a bottom view of the sixth embodiment.

FIG. 37 shows a perspective view of a seventh embodiment of a design for an integrated tabbed note and clip kit.

FIG. 38 shows a top view of the seventh embodiment.

FIG. 39 shows a front view of the seventh embodiment.

FIG. 40 shows a right-side view of the seventh embodiment. A left-side view of this embodiment is a mirror image of this figure.

FIG. 41 shows a back view of the seventh embodiment.

FIG. 42 shows a bottom view of the seventh embodiment.

FIG. 43 shows a perspective view of an eighth embodiment of a design for an integrated tabbed note and clip kit.

FIG. 44 shows a top view of the eighth embodiment.

FIG. 45 shows a front view of the eighth embodiment.

FIG. 46 shows a right-side view of the eighth embodiment. A left-side view of this embodiment is a mirror image of this figure.

FIG. 47 shows a back view of the eighth embodiment.

FIG. 48 shows a bottom view of the eighth embodiment.

FIG. 49 shows a perspective view of a ninth embodiment of a design for an integrated tabbed note and clip kit.

FIG. 50 shows a top view of the ninth embodiment.

FIG. 51 shows a front view of the ninth embodiment.

FIG. 52 shows a right-side view of the ninth embodiment. A left-side view of this embodiment is a mirror image of this figure.

FIG. 53 shows a back view of the ninth embodiment.

FIG. 54 shows a bottom view of the ninth embodiment.

FIG. 55 shows a perspective view of a tenth embodiment of a design for an integrated tabbed note and clip kit.

FIG. 56 shows a top view of the tenth embodiment.

FIG. 57 shows a front view of the tenth embodiment.

FIG. 58 shows a right-side view of the tenth embodiment. A left-side view of this embodiment is a mirror image of this figure.

FIG. 59 shows a back view of the tenth embodiment.

FIG. 60 shows a bottom view of the tenth embodiment.

FIG. 61 shows a perspective view of an eleventh embodiment of a design for an integrated tabbed note and clip kit.

FIG. 62 shows a top view of the eleventh embodiment.

FIG. 63 shows a front view of the eleventh embodiment.

FIG. 64 shows a right-side view of the eleventh embodiment. A left-side view of this embodiment is a mirror image of this figure.

FIG. 65 shows a back view of the eleventh embodiment.

FIG. 66 shows a bottom view of the eleventh embodiment.

FIG. 67 shows a perspective view of a twelfth embodiment of a design for an integrated tabbed note and clip kit.

FIG. 68 shows a top view of the twelfth embodiment.

FIG. 69 shows a front view of the twelfth embodiment.

FIG. 70 shows a right-side view of the twelfth embodiment. A left-side view of this embodiment is a mirror image of this figure.

FIG. 71 shows a back view of the twelfth embodiment.

FIG. 72 shows a bottom view of the twelfth embodiment.

FIG. 73 shows a perspective view of a thirteenth embodiment of a design for an integrated tabbed note and clip kit.

FIG. 74 shows a top view of the thirteenth embodiment.

FIG. 75 shows a front view of the thirteenth embodiment.

FIG. 76 shows a right-side view of the thirteenth embodiment. A left-side view of this embodiment is a mirror image of this figure.

FIG. 77 shows a back view of the thirteenth embodiment.

FIG. 78 shows a bottom view of the thirteenth embodiment.
